LIFTING MAGNET

David E. Scott, Royal Oak, Mich., assignor to Square D Company, Park Ridge, Ill., a corporation of Michigan

Filed May 28, 1962, Ser. No. 70,308

Term of patent 14 years

(Cl. D41—1)

FIG. 1 is a perspective view of a lifting magnet showing my new design;

FIG. 2 is a reduced scale top plan view thereof;

FIG. 3 is a reduced scale right side elevational view thereof;

FIG. 4 is a reduced scale front elevational view thereof; and

FIG. 5 is an enlarged fragmentary cross sectional view taken on the line 5—5 of FIG. 2.

The dominant features of my design reside in the full line portion of the drawing.

I claim:

The ornamental design for a lifting magnet, as shown and described.
